DESIGN FOR A SMOOTHING IRON

Paul E. Ambory, Hazel Park, Mich.

Application December 13, 1946, Serial No. 135,495

Term of patent 14 years

(Cl. D49—6)

To all whom it may concern:

Be it known that I, Paul E. Ambory, a citizen of the United States, residing at Hazel Park, in the county of Oakland and State of Michigan, have invented a new, original, and ornamental Design for a Smoothing Iron, of which the following is a specification, reference being had to the accompanying drawings, forming a part thereof, and in which:

Fig. 1 is a top plan view of a smoothing iron showing my new design,

Fig. 2 is a side elevational view,

Fig. 3 is a front elevational view,

Fig. 4 is a cross sectional view taken on line 4—4 of Fig. 2.

What I claim is:

The ornamental design for a smoothing iron, as shown.

PAUL E. AMBORY.
